SELECTIVE AMPLIFIER

Application filed June 8, 1929. Serial No. 369,383.

This invention relates to amplifiers of electrical variations wherein one of the component parts is an electron-discharge device, but more especially the invention relates to 5 selective amplifiers such as are used for instance in transmission and reception of radio telegraphy and telephony, or in any other application in which it is desired to amplify a specific frequency or band of frequencies.

10 An especial object of this invention is the provision of an amplifier system capable of amplifying a predetermined frequency to the exclusion of other frequencies.

A further object of the present invention 15 is the reduction of the effective electro-static capacity between grid and plate by lowering the resistance into which the plate circuit is connected, thereby eliminating to a large extent the tendency to "feed-back" and oscillate.

A still further object of the present invention is the provision of a selective amplifier in which the signal static ratio is considerably increased.

25 Figure 1 is a diagrammatic drawing of an electron-discharge device V which may be of the conventional three electrode type or may be of the type described in my co-pending application Serial No. 358,774, filed April 29, 30 1929, and/or my co-pending application Serial No. 363,201, filed May 15, 1929. The battery A serves to maintain the filament f at a temperature necessary to produce sufficient electron emission from the cathode c. The 35 ionization shield s surrounds the cathode as in my co-pending application Serial No. 358,774, filed April 29, 1929. The battery B serves to supply voltage for the plate-cathode circuit. A source of input potential, such as 40 for instance a tuned radio-frequency transformer T, is connected at its opposite ends to the cathode c and the grid g. The output or load circuit consists of the resister Rx shunted by the tuned circuit LC, points 1 and 45 2 thereof constituting the output terminals which may be connected to a detector or to the input terminals of an amplifier such as herein disclosed if more than one stage of amplification is desired.

50 In accordance with the well-known action

of the three electrode electron-discharge device, variations of the potential of the grid g will cause a current to flow in accordance therewith through the circuit including the plate-cathode path.

This invention anticipates the use of a resonant circuit consisting of inductance and capacity, either one of which or both may be variable (herein the capacity is shown as the variable element) as a portion of the plate-circuit load. In contra-distinction to conventional practice, I introduce a current into a series resonant circuit instead of a potential into a parallel resonant circuit.

In order to more readily understand the 65 advantages of this invention, it must be realized that the effective impedance between the opposite terminals of a series resonant circuit (to resonant frequency) is equal to the value of the resistance included between the opposite terminals. The total voltage introduced into such a series resonant circuit drops across this resistance, shown as R_L , and with a given current the potential across the inductance L and the condenser C may be 70 many thousand times greater than the voltage introduced between the opposite terminals of the series resonant circuit.

In accordance with the above, I pass the 75 alternating component of the plate circuit through a load consisting of the resister R_x shunted by the series resonant circuit L— R_L —C. At the resonant frequency the effective impedance between points 1 and 3 is equal to R_x shunted only by R_L , since the reactances of L and C are equal and opposite. During this condition, if R_x is equal to R_L , which is the optimum, one half of the A. C. plate current will flow through R_x , while the other half will flow through the 80 series resonant circuit above referred to, and although the potential across R_x may be extremely small, the potential across either the inductance or the capacity will be equal to the product of the A. C. current flowing therethrough, and the reactance of the condenser or inductance. It is therefore evident that a relatively high degree of amplification 85 may be obtained with this system, coincidently with a high degree of selectivity and 90 95 100

with a very small effective resistance in the plate circuit of the electron-discharge device forming a portion of the amplifier.

One of the principal advantages of the present invention, however, is the fact that although the resonant circuit is amply selective and possesses low decrement to the signal frequency, the decrement offered to a transient disturbance, such as for instance atmospheric disturbances, is twice that offered to the signal frequency (if R_x is equal to R_L).

It is generally believed that the objectionable noises due to atmospheric disturbances in radio receiving systems are caused principally by "impulse excitation" of the resonant circuit. In other words, a transient disturbance such as "static" causes the tuned circuit to oscillate for a few cycles at the frequency to which it is tuned, the amplitude of the oscillation and the time duration thereof being dependent upon the decrement or effective resistance of the tuned circuit. By use of the present system, I am enabled to secure the same degree of signal selectivity as with conventional parallel resonant circuits, co-incidently with a very high and adjustable decrement or resistance to transient response.

If, for instance, R_x is made a variable resistance, the response to signal may be increased co-incidently with an increase in the decrement offered to transient disturbances, but at slight sacrifice of signal selectivity.

Inasmuch as this invention utilizes the electron-discharge devices as current and not as voltage generators, electron-discharge devices having a low value of plate resistance and a high value of mutual conductance are desirable. Since only the mutual conductance contributes toward the degree of amplification obtained in the present system, it is unnecessary and inadvisable to utilize electron-discharge devices having a high value amplification factor.

In order to utilize to best advantage the high decrement which this system offers to transient impulses when used in radio receiving systems, the antenna should be connected to the grid of the electron-discharge device aperiodically and not by a tuned transformer as shown on the drawing.

The amplifier herein shown and described consists of only one stage but more than one stage may be employed where necessary and desirable, and although I have herein shown batteries as power supply sources, it is understood that such power may be supplied in other ways, as for instance, from commercial power circuits with the necessary rectifiers and filters.

Although I have herein shown and described but one form of my present invention, I do not limit myself thereto, inasmuch as modifications and changes may be made

therein without departing from the original spirit of the invention or the scope of the appended claims.

What I claim is:

1. A selective amplifier of electrical variations consisting of an electron-discharge device, a suitable source of input signal potential, power supply sources for cathode and anode circuits, and an anode output net-work consisting of a non-inductive resister shunted by a condenser and an inductance forming a series circuit resonant to the frequency of the input signal potential, said non-inductive resister having a value approximating that of the tuned circuit resistance at signal frequency. 70

2. A coupling medium for selective electron-discharge amplifiers consisting of a non-inductive resistance shunted by a series resonant circuit, said non-inductive resistance having a value approximating that of the tuned circuit resistance at signal frequency output circuit of preceding electron-discharge device being connected across the non-inductive resistance and input circuit of succeeding electron-discharge device being connected across one of the elements forming the above mentioned series resonant circuit. 80

3. A selective output net-work for electron-discharge amplifiers consisting of a non-inductive resistance adapted to be connected in series with the plate-cathode path of an electron-discharge device and a series resonant circuit in parallel with the non-inductive resistance, said non-inductive resistance having a value approximating that of the tuned circuit resistance at signal frequency. 90

4. In an amplifier of electrical variations, selective to a particular frequency, one or more electron-discharge devices, suitable power supply sources therefor, and a coupling media between said electron-discharge devices consisting of a non-inductive resister shunted by a series resonant circuit, said non-inductive resister having a value approximating that of the tuned circuit resistance at signal frequency and being connected in series with preceding plate-cathode circuit, and grid-cathode of succeeding electron-discharge device being connected across a portion of said resonant circuit. 100

In testimony whereof, I have signed my name to this specification.

ALGER S. RIGGS.
